UNITED STATES PATENT OFFICE.

MORRIS ABBOTT, OF COLUMBUS, OHIO.

VEHICLE-CURTAIN.

1,358,491.

Specification of Letters Patent.

Patented Nov. 9, 1920.

Application filed March 1, 1919. Serial No. 280,059.

To all whom it may concern:

Be it known that I, MORRIS ABBOTT, a citizen of the United States, residing at Columbus, in the county of Franklin and State of Ohio, have invented certain new and useful Improvements in Vehicle-Curtains, of which the following is a specification.

This invention relates broadly to vehicle curtains, and has specific reference to improved means for effecting the securing of a transparent vision panel in an operative position within such curtains.

The object of the invention is to provide simple and inexpensive means for quickly effecting the mounting of a celluloid or isinglass panel within the curtain of an automobile top, and to accomplish this result without necessitating the removal of the curtain from its coöperative frame, and further, to eliminate the necessity of stitching the panel to the curtain.

To this end, the invention broadly consists of a flexible frame strip which is capable of being bent to assume requisite opening configurations and to provide this strip with attaching elements, which are adapted to penetrate the celluloid panel and the curtain to which it is applied, whereby upon the clenching of the ends of the securing elements the panel and strip structure as a whole will be securely supported in connection with a curtain and a pleasing and finished appearance afforded.

The essential object, therefore, of the present invention consists in the provision of the flexible frame strip, which is so constructed as to be readily applied in connection with curtain openings of all configurations and which serves to quickly and firmly unite the transparent panel coöperative therewith in an applied position upon a curtain.

With these and other objects in view as will appear as the description proceeds, the invention accordingly consists in the novel features of construction, combination of elements and arrangement of parts hereinafter fully described, and having the scope thereof pointed out in the appended claim.

50 In the accompanying drawing, forming a part of this specification:

Figure 1 is a plan view of the frame strip employed by the invention.

Fig. 2 is a fragmentary front elevation of 55 the strip, showing the same as applied to a

vehicle curtain and its coöperative transparent panel,

Fig. 3 is a vertical sectional view taken along the line 3—3 of Fig. 2,

Fig. 4 is an elevation looking at the inside 60 of the curtain and disclosing more particularly the securing elements employed for retaining the strip in secured relation with a curtain, and

Fig. 5 is an exterior elevation, showing the 65 application of the strip to a curtain window.

Similar characters of reference denote like and corresponding parts throughout the several views of the drawing.

Heretofore, it has been a common practice 70 in the art to secure a transparent panel to a vehicle curtain by simply stitching the edges of the panel to the curtain. This necessitates the removal of the latter from its position upon its coöperative frame, which 75 is a labor involving operation and frequently results in tearing or mutilating the curtain to such extent that it is either rendered useless or, at least, permits of the seepage of moisture into the interior of the vehicle 80 with which the curtain is associated. To overcome this objection, other improvements in the art have provided rigid metallic clamping frames which provide means for securing a transparent panel in position 85 without necessitating the removal of the curtain from its frame. These latter constructions, however, are open to the particular objection that the same must be made in many and numerous sizes and shapes to fit 90 the various designs of vision openings provided in vehicle curtains, and as a result a dealer must carry a very extensive variety of these frames to meet the trade requirements. To overcome the above objections, 95 and to provide a device which will be applicable to openings of any design, the present invention comprises a flexible frame strip 1, which is preferably formed from rubber or a composition thereof and may be sold in 100 any desired length so as to be capable of surrounding the bounding edges of a vision opening 2 provided in the curtain 3 of a vehicle top. This strip 1 is adapted to co-operate with the transparent panel 4 of 105 celluloid employed in covering the opening 2 and is provided with means for securely clamping the panel in its applied position with respect to said opening. To effect this result said strip is provided at intervals 110

throughout its length with a plurality of pliable securing elements 5 which, in their preferred form, are suitably embedded within and carried by the strip 1. These elements are provided with pointed extremities so as to enable the same to readily penetrate the panel 4 and the surrounding or adjacent portions of the curtain 3. A reinforcing strip 6 is positioned along the interior surface of the curtain 3 and is preferably formed from the same material as the strip 1, so as to be capable of readily conforming to the configuration of the opening 2. The ends of the securing elements also penetrate this reinforcing strip and, as shown, are bent or clenched over so as to lie parallel with the strip 6 and to thereby bind the frame strip 1 into firm securing relation with respect to the panel 4.

From the foregoing, it will be apparent that in the event of fracture on part of the panel 4 the injury may be repaired by merely securing a new panel and in forming the latter so that its marginal portions will slightly overlie the edges of the opening 2. This panel may be then held in position by forcing the elements 5 of the strip 1 therethrough and by clenching the ends of the elements, as above mentioned, in coöperation with the reinforcing strip 6. It will be observed that this operation can be readily effected without requiring the removal of the curtain from its coöperative frame, and also, the strip 1, on account of its flexible

nature may be readily shaped to correspond with the formation of the panel and it therefore eliminates the necessity of numerous sizes. When in an applied position the strip 1 will conceal the joints between the panel 4 and the curtain 3 and will therefore present a pleasing and artistic exterior appearance. By virtue of the reinforcing strip 6 and the securing elements 5 the parts of the construction may be securely bound together so that the flow of moisture between parts will be effectively eliminated. To effect repairs in the construction it is simply necessary to purchase a sufficient length of the strip 1 to surround a desired curtain opening, as the necessity of taking cognizance of the opening configuration has, on account of the flexible strip 1, been eliminated. This serves to materially reduce the cost of making such repairs and permits the same to be accomplished with ease and facility.

What I claim is:

A light frame for vehicle curtains, comprising a one piece flexible strip of rubberized material of such form as to be capable of surrounding the marginal portions of the light opening of a curtain, and a plurality of pliable prongs permanently carried by said strip and having the heads thereof embedded therein, said prongs being capable of penetrating said curtain to securely unite said strip in applied relationship therewith.

In testimony whereof I affix my signature.
MORRIS ABBOTT.
